FUEL FEEDING APPARATUS

Walter S. Landon, Detroit, Mich., assignor to Detroit Lubricator Company, Detroit, Mich., a corporation of Michigan

Application March 23, 1944, Serial No. 527,682

11 Claims. (Cl. 158—36)

1

The invention relates to a device for controlling the flow of fluids and it has particular relation to a valve means for controlling flow of fuel to an oil burner.

In the operation of oil burners, for instance, the flow of liquid fuel may be governed by adjustable valve means so as to control the degree of fire. This control may be automatically effected by suitable thermal means. However, in the operation of ordinary systems of this character, the flow of fuel will vary or even stop altogether due to the presence of foreign elements or ingredients, such as wax, which collect around the valve opening. While one might have means for actually varying the supply of fuel oil and varying the fire in accordance with heat requirements, these results have not constantly been obtained due to wax or the like which collects and alters any initially determined relation of parts.

One object of the present invention is to provide an improved heating system wherein the disadvantages mentioned above are avoided so that the fuel burner may be accurately controlled over an indefinite period of time.

Another object of the invention is to provide a system of this character which is adjustable so as to obtain the improved results desired while still allowing for a wide range of variation in amount of oil supplied to the fuel burning equipment.

Another object of the invention is to provide an improved form of thermal controlled valve for obtaining an adjustably controlled supply of fuel oil and maintaining the supply constant over a long period of time.

Other objects of the invention will become apparent from the following description, from the drawing to which it relates and from the claims hereinafter set forth.

For a better understanding of the invention reference may be had to the accompanying drawing wherein:

Figure 1 is a diagrammatical view illustrating a heating system constructed according to one form of the invention and showing the improved form of valve involved in cross-section;

Figure 2 is a detailed view illustrating operation of the valve metering pin with the valve adjusted for the purpose of supplying a large quantity of oil;

Figure 3 is similar to Figure 2, but shows the valve movement when a small amount of oil is being supplied; and

2

Figure 4 is a view illustrating a modified type of valve metering pin.

Referring to Figure 1, the system in general may include an oil supply line 10, a float control 11, a valve 12 for governing the supply of fuel oil to a burner, and a burner 13. The valve is shown on an enlarged scale and in cross-section, and it should be understood that the liquid may be maintained at a predetermined level by the float, as for instance, at the line 14 in the valve casing. The burner 13 may supply heat to a furnace for the purpose of heating a room or other space and a thermostat 14 adapted to be in such space may be employed for governing operation of the system. Also, a motor 15 is shown in broken lines, and the motor may drive a blower so as to supply air to the burner 13 in order that the oil will burn. It may be assumed for the purpose of the present invention, that the motor 15 is driven constantly at a predetermined speed, although it may be so controlled that when a high fire is required in the burner the motor will operate at a higher speed and when a low fire is to be maintained the motor 25 will operate at a low speed.

The valve casing 12 is provided with an intermediate horizontal wall 18 which has a cylindrical opening 19 at one point through which the oil flows from an upper chamber 20 in the casing to a lower chamber 21 in the casing. From the latter chamber the oil flows through a line 22 to the burner. Flow of oil through the opening 19 is governed by a metering pin 24 which is slidable vertically in an opening 25 in a boss 26 on the upper side of the wall 18. This boss has a transverse opening 27 through which oil may flow to the opening 19.

The metering pin 24 has a larger upper portion 29 which is vertically reciprocatory through an opening 30 in an upper partition 31 fastened to the lower part of the valve casing by screws 32. These screws also fasten an upper cover 33 for the valve casing, and the cover is of such character as to provide an upper chamber in addition to the two lower chambers. At its upper end the larger portion 29 of the metering pin is vertically guided in an opening 34 in the upper wall of the cover.

In addition to governing the flow of fuel oil through the opening 19, it is desired to clear or clean the opening, as well as the end of the metering pin, so as to remove wax or other material which may collect and interfere with the flow of fuel oil. This is accomplished in the present invention by moving the valve pin in a vertically

reciprocatory manner so that it repeatedly moves through the valve opening while still being withdrawn sufficiently during each opening movement so as to allow fuel oil to flow through the opening. In the first instance, it may be said that it is desired to have the metering pin move entirely through the opening on each stroke so as to immediately clean or clear the valve and, secondly, that the pin be withdrawn on each upward movement a sufficient amount to allow the desired quantity of oil to flow through the opening. Additionally, it is desired to vary the movement of the pin so that the amount the pin is withdrawn may be adjustably varied in order to adjustably vary the rate of oil flow.

In accomplishing these results according to the present invention, a lever 36 is provided in the upper chamber and this lever is pivoted as indicated at 37 on a collar 38 fixed to a vertically reciprocating pin 39. This pin is guided in openings 40 and 41 in the partition 31 and in the upper wall of cover 33, respectively, and a spring 43 engaging the partition 31 and the collar 38 normally urges the pin 39 in an upward direction.

The lever 36 is in contact with a pin 46 on the upper part 29 of the metering pin 24 and the outer end of the lever passes through an opening 47 in the side wall of cover 33 and is engaged by an eccentric 48 on the shaft 49 of the motor 15. It should now be seen that if the pivot 37 is held in position, rotation of motor 15 will move the lever 36 downwardly as the higher side of the eccentric moves toward the lower side of the motor shaft. Upward movement of the valve metering pin and the lever 36 is effected by means of a coil spring 50 around the lower end portion of the metering pin, and which engages at its upper end a collar 51 on the metering pin, and at its lower end the upper side of the boss 26. It is now evident that the eccentric operating in conjunction with the coil spring 50 will cause the metering pin to reciprocate vertically in accordance with the position of the eccentric.

The position of the fulcrum or pivot 37 vertically may be limited by adjustable screws 54 and 55 threaded through the upper wall of the cover 33 and having collars 56 and 57 on their lower ends disposed at the upper and lower sides, respectively, of a collar 58 fixed on the pin 39. Movement of the fulcrum 37 downwardly is thermally effected by means of a bi-metal element 60 secured to a bracket 61 fastened by means of a screw 62 to a projection 63 on the cover 33. This thermal element has a heating element 65 fastened to it and the heating element may be energized by means of wires 66 and 67 forming part of a circuit, including a transformer 68 and a contact 69 adapted to be engaged by a contact 70 on the thermostat. The transformer is shown in an electric circuit including power lines 71 and 72 having wires 73 and 74 leading to the motor 15. The free end of the thermal element 60 overlies the collar 38 on pin 39.

With the parts as illustrated, the burner is operating at high fire with the thermostat 14 closed, thereby requiring more heat for the space to be heated. Under these conditions, the thermal element 60 is expanded so as to cause the free end thereof to be raised and the spring 43 has moved the collar 38 and pin 39 upwardly as far as permitted. Hence, the pivot or fulcrum 37 is at its upper limit. Operation of the motor 15 causes the valve metering pin to vertically reciprocate and since the fulcrum 37 is at its upper limit, the pin moves vertically between the full

and broken line positions, as seen in Figure 2. Thus, while the pin passes entirely through the valve opening 19 so as to effect the cleaning or clearing of the valve, the pin is withdrawn a greater amount during the upward movements thereof, and hence the valve is opened a larger amount so that a larger quantity of oil flows to the burner. It will be realized even though the metering pin is reciprocating that oil may flow through the opening during the times that the pin is withdrawn.

After the space has been heated sufficiently, the thermostat 14 operates to interrupt the circuit to the heating element 65 and then upon 15 cooling of the thermal element 60, the free end thereof moves the collar 38 and fulcrum 37 downwardly. The movement of the fulcrum 37 downwardly lowers the fire gradually until the collar 58 on pin 39 engages the lower limiting collar 57, at which time the oil will be supplied at a constant but low rate. Figure 3 illustrates the movement of the metering pin 24 at this low stage of fire and it will be seen that a smaller amount of oil flows through the opening 19 while still effecting the cleaning as previously mentioned. Attention is directed to the fact that the lower end of the metering pin 24 is of conical shape, as indicated at 76, and under some circumstances this is desirable so as to insure movement of the pin into and through the opening and also to obtain a more desirable fuel flow controlling action.

When the space to be heated requires more heat, the thermostat closes and then the thermal element 60 begins to expand and the metering pin in turn allows a gradually increasing supply of oil to be delivered to the burner. Finally, the thermal element expands sufficiently so as to allow the pivot 37 to reach its upper limit 30 and then oil is supplied at the higher rate. During these operations, the motor constantly rotates so that the metering pin is being reciprocated vertically at all times.

The foregoing description relates to the normal operation of the valve mechanism. In the event the motor 15 should stop for any reason, however, with the high side of the eccentric 48 at the upper side of the shaft 49, the valve stem would be left in an open position and this would allow a full flow of oil to the burner for an indefinite period of time. For the purpose of avoiding this condition, a safety means is provided for closing the valve in the event the motor stops with the valve open which includes a dashpot 55 formed by a cylindrical well 77 in the wall 31, a piston 78 and a coil spring 79 below the piston. A short rod 80 connected to the piston abuts one end of an arm 81, pivoted intermediate its ends to the cover 33 as indicated at 82 and a projection 83 on the lever 36 is adapted to engage the upper side of the arm 81 in alignment with the rod 80. At the opposite side of the pivot 82, the arm 81 has its end positioned for engagement with a pin 85 on the valve stem.

In order to allow air to enter the dashpot below the piston 78, the latter may have a small opening 78a of such size that once the piston is in its lower position, a substantial period of time, for instance 10 to 15 seconds, would be required to allow enough air to enter the dashpot below the piston to cause the required upward movement of the piston. The piston may have a check valve 78b which would allow air to rapidly escape from the space beneath the piston 75 but not to enter through the valve and a second

and smaller opening 78 for allowing only a slow inlet of air into the space below the piston. By having two openings of this character, the piston could be moved downwardly rapidly but could only move upwardly at a slow rate.

As the lever of the valve mechanism begins to function, it causes the piston in the dashpot to move downwardly and then the constant movement of the arm maintains the piston in the position shown. If the motor should stop with the high side of the eccentric at the upper side of the shaft 49, the arm 36 would come to a stop in its uppermost position and then the dashpot would begin to function so as to move the arm 81 about its pivot 82, it being understood that the projection 83 would at this time be above and spaced from the arm 81. Movement of the arm 81 by the dashpot would cause movement of the valve stem downwardly through engagement of the arm with the pin 85. It should be understood that the parts are so related, including the springs 79 and 80, that the spring 79 would overcome the spring 80 so as to effect closing of the valve, in the event the motor stops as indicated. While the dashpot has been shown between the valve stem 24 and the pin 89, it could be located directly beneath the outer end of the arm 36, or in other words, underneath the eccentric 48. This might be desirable under certain circumstances in order to place the dashpot device at a greater distance from the fulcrum 37. In either case, however, it is to be understood that constant movement of the arm 36 downwardly would hold the piston in its lower position in the dashpot and that upon stopping of the arm in an upper position the dashpot would begin to function so as to swing the arm 81 and close the valve. In other words, the dashpot would function at the right side of the valve stem instead of at the left side.

In Figure 4, instead of using a valve metering pin having a conical surface 76 on its lower end, the pin has a conically shaped lower end but the sides of the cone have annular steps 87, each of which is formed by an upper radial wall 88 and a lower inclined wall 89 so as to provide a relatively sharp edge. In some circumstances, this may be desirable so as to more easily and more efficiently clear the valve opening of wax or other material and to cause the material to be carried to the lower side of wall 18. It should be understood that the metering pin in this case will move through the opening in the same manner as previously described.

Although more than one form of the invention has been illustrated and described in detail, it will be apparent to those skilled in the art that various modifications may be made without departing from the scope of the appended claims.

What is claimed is:

1. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame and including a lever and a continuously rotating eccentric engaging said lever, an adjustable member pivotally supporting said lever and movable to regulate the extent of withdrawal of said valve member from said outlet, means to adjust said adjustable member, and safety means operable to move

said valve member into said outlet upon stoppage of said reciprocating means.

2. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame and including a lever and a continuously rotating eccentric engaging said lever, said valve member having an abutment engageable with said lever, a spring urging said valve member from said outlet and urging said abutment against said lever and said lever against said eccentric, a safety spring operable to overcome said first-named spring and to move said valve member into said outlet, a dashpot effective for the interval during valve member releasing movement of said lever to hold said safety spring against operation, and means operable by said lever to render said dashpot effective.

3. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame and including a lever and a continuously rotating eccentric engaging said lever, an adjustable member pivotally supporting said lever and movable to regulate the extent of withdrawal of said valve member from said outlet, means determining a first position of said adjustable member for a high burner flame, means determining a second position of said adjustable member for a low burner flame, and means to move said adjustable member to and to hold said adjustable member in said positions.

4. Fuel feeding means for a liquid fuel burner, comprising a casing having a constant level chamber with an outlet below the liquid level, a valve member constructed to fit said outlet to clean the same and regulate flow therethrough, means to reciprocate said valve member at a rate to supply fuel for a constant burner flame and including a lever and a continuously rotating eccentric engaging said lever, an adjustable member pivotally supporting said lever and movable to regulate the extent of withdrawal of said valve member from said outlet, means determining a first position of said adjustable member for a high burner flame, means determining a second position of said adjustable member for a low burner flame, a spring urging said adjustable member against one of said determining means, and automatic means operable to overcome said spring and move said adjustable member to the other of said determining means.

5. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame and including a lever and a continuously rotating eccentric engaging said lever, an adjustable member pivotally supporting said lever and movable to regulate the extent of withdrawal of said valve member

from said outlet, a bimetal member operable to adjust said adjustable member, and an electric means for heating said bimetal member.

6. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame, automatically acting safety means normally tending to move said valve member into said outlet, and means to render said safety means inactive.

7. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame, automatically acting safety means normally tending to move said valve member into said outlet, and means actuated by said reciprocating means to render said safety means inactive.

8. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame, time delay means operable upon stoppage of said reciprocating means in valve member open position to move said valve member into said outlet, and means operable by said reciprocating means to render said delay means ineffective.

9. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame, said valve member being operable to have independent movement relative to said reciprocating means, a spring cooperable with said valve member and operable upon stoppage of said reciprocating means in

5 valve member open position to move said valve member relative to said reciprocating means and into said outlet, a dashpot operable to hold said spring against operation, and means operable by said reciprocating means to render said dashpot effective.

10 10. Fuel feeding means for a liquid fuel burner, comprising a casing having a constant level chamber with an outlet below the liquid level, a valve member constructed to fit said outlet and reciprocal into and from said outlet to clean the same and regulate flow therethrough, means to reciprocate said valve member at a rate to supply fuel for a constant burner flame, means controlling said valve member to supply fuel for a higher constant burner flame and including automatic means gradually varying the quantity of fuel supplied during the transition between said higher constant flame and said first-named constant flame.

15 11. A fuel flow controlling device comprising a casing having a passageway for flow of fuel, said passageway having a valve opening, a reciprocally movable metering pin cooperable with said opening, means normally urging said pin toward open position, means for reciprocating said pin in a substantially continual manner at a rate operable to maintain a constant burner flame, automatically acting safety means for moving said pin to valve closed position in the event that said reciprocating means should stop operating with said pin in an open position, and said safety means being operable to oppose and to overcome said normally urging means for safety operation.
